SEWING CHEST

Isidore Rothstein, Bronx, N. Y., assignor to Kate Jacobson, Bronx, N. Y.

Application July 15, 1950, Serial No. 11,215

Term of patent 3½ years

(Cl. D3—19)

To all whom it may concern:

Be it known that I, Isidore Rothstein, a citizen of Russia, residing in the Borough and county of the Bronx, State of New York, have invented a new and ornamental Design for a Sewing Chest, of which the following is a specification, reference being had to the accompanying drawing, forming a part hereof:

In the drawing:

The bottom and back of the sewing chest are plain. Both sides are identical to the showing in Figure 4.

I claim:

The ornamental design for a sewing chest, substantially as shown and described.

ISIDORE ROTHSTEIN.
